MINING DRILL

Elmer J. Huckhold, St. Louis, Mo., assignor to
 Central Mine Equipment Company, St. Louis,
 Mo., a corporation of Missouri

Application October 12, 1949, Serial No. 120,997

5 Claims. (Cl. 255—69)

1

This invention relates generally to mining drills, and particularly to drills of the character wherein the cutting bits are removable and replaceable, being held in position by a wedge.

Mining drills of the character above referred to are in common use, typical examples being shown by the patents of Cook, Nos. 2,010,509, 2,010,510, 2,109,613, and 2,237,133. Such mining drills are provided with a permanent head, adapted to be associated with an auger, and rotated by a suitable driving mechanism. In the head, a plurality of sockets are provided for the reception of removable bits and their retaining wedges. When it is desired to change bits, as for example when the same have become dull, the inner end of the wedge is struck a blow or so with a hammer to loosen the wedge within its socket, and consequently free the bits for replacement. Conversely, when the new bit has been inserted in position, the outer end of the wedge is struck a blow or so with a hammer to tighten the wedge about the bits within the socket. Wedge and socket arrangements in great variety have been provided in the art, the criterion being that the wedge have one end (usually the outer) exposed to receive a blow in a direction which will tighten the wedge and bits in the socket, and that it have its other end exposed to receive a blow which will loosen the wedge and bit assembly within the socket.

In the normal use of such mining drills, vibration of the bits tends to, and frequently does, loosen the assembly of bit and wedge, with resultant loss of the parts. The bits are quite commonly of the "throw away" type, but the wedge is intended to be a permanent part of the apparatus.

The object of the present invention, generally stated, is to provide a mining drill of the character aforesaid, wherein the wedge is secure against accidental loss from the socket in the head.

A further object of the invention is to provide a mining drill of the character aforesaid, wherein loosening of the wedge during normal operation is inhibited.

Other objects will become apparent to those skilled in the art when the following description is read in connection with the accompanying drawings, in which:

Figure 1 is a view in side elevation of a mining drill head, having a wedge and bit assembly constructed in accordance with the present invention;

Figure 2 is a sectional view taken along line 2—2 of Figure 1; and

5

Figure 3 is a perspective view of a typical wedge as employed in the head shown in Figure 1, but provided with the anchoring means of the present invention.

Generally stated, the present invention contemplates the provision of a removable anchoring pin in a wedge of the character aforesaid. The anchoring pin is inserted through a hole provided in the exposed rear end of the wedge, so as to extend into contact with, and be deformed by, engagement with the wall of the socket within which the wedge is received. In order to accommodate the interior end of the anchoring pin, and assist in deforming it, the wedge is preferably provided, at a location within the socket, with a recess of a volume sufficient to tightly accommodate the projecting end of the anchoring pin. The anchoring pin is preferably resilient, and may be an ordinary cotter key, which is extended through the wedge so that its free end (on the interior of the socket) extends in the direction which the wedge must be moved to loosen the assembly within the socket. Such an anchoring pin not only inhibits loosening of the wedge, but positively prevents loss of the wedge in the event of accidental loosening, even though the bits may be lost.

Referring now to the drawings, the head shown in Figure 1 is provided with a pair of sockets 1, each adapted to receive a pair of cutting bits 2, held in position within the socket by a wedge 3. In the form shown in the drawing, the socket 1 is tapered, being of larger area at the upper end than at the lower end. The wedge 3 is similarly tapered, so that even in the absence of the bits 2, the wedge 3 cannot move downwardly through the socket so as to become lost. Accordingly, the only direction in which the wedge may be removed from the socket is by movement of the wedge upwardly relative to the socket.

The particular form of wedge 3 shown in the drawings is merely illustrative of a great variety of forms which such wedges customarily take, and the invention is not limited to the configuration of the wedge as shown.

The present invention contemplates the provision of a hole 4 in the rear end, which is the smaller end, of the wedge 3. On the side of the wedge 3, which is concealed when the wedge is in operative position, the mouth of hole 4 is enlarged, as shown at 5, the degree of enlargement depending upon the volume of the extremity of the anchoring pin to be accommodated therein.

An anchoring pin 6 is inserted in hole 4 after the wedge 3 is in position within socket 1, and

driven home, so that only the head thereof extends beyond the outer surface of wedge 3. The pin 6 is considerably longer than hole 4, so that a substantial extremity of the pin 6 is bent over and deformed within recess 5, against the inner wall of socket 1, as shown clearly in Figure 2. Such deformation of the pin 6 not only provides a resilient anchorage against the interior wall of the socket, but also prevents the pin 6 from falling out of the hole 4. While the pin 6 is in position within the hole 4, the wedge 3 cannot be removed from its socket 1. The deformation of the pin 6 which occurs upon its being driven into contact with the interior wall of the socket is, however, not such as to positively prevent the removal of the pin 6 by forces which may be applied directly to its head. Accordingly, a sufficient draft applied at the head of pin 6, in the direction in which the hole 4 extends, will accomplish removal of the pin 6 when it may be desired to remove the same, so as to free the wedge 3 for removal. The pin 6 need not be removed to replace the bits 2, however. Although a harder blow is required to remove wedge 3 within its socket when the pin 6 is in place than when no such pin is provided, the degree of anchorage provided by the pin 6 is not such as to prevent the movement of the wedge relative to the socket under heavy hammer blows, to an extent sufficient to free (in one direction) and tighten (in the other direction) the bits.

From the foregoing description, those skilled in the art should readily understand the structure and operation of the anchorage, and realize that it accomplishes its objects. While a full disclosure of one embodiment of the invention has been given, it is to be distinctly understood that the precise form of drill head, socket, wedge, and bit shown in the accompanying drawings is merely illustrative, and that the anchorage of the present invention is applicable to all such wedge, socket, and bit assemblies, irrespective of the precise form thereof, provided there is some exposure of the wedge behind the socket, or in the direction from which the wedge must be driven to loosen it. It is therefore to be distinctly understood that the invention is not limited to the precise form shown, but that it is applicable at large to such drill heads, and is susceptible of many modifications, without departing from the spirit of the present invention, or the scope of the appended claims.

Having thus described the invention, what is claimed and desired to be secured by Letters Patent is:

1. In a mining drill head having detachable bits, a wedge for retaining the bits in position and a socket for accommodating the wedge, the improvement which comprises a resilient pin accommodated in a hole in said wedge, one end of said pin being exposed beyond the boundaries of said socket for a distance sufficient positively to prevent removal of said wedge from said socket, and the other end frictionally engaging

an interior wall of said socket at a position concealed by the wedge.

2. For use with a mining drill having a socket for the reception of a bit and a retaining wedge; the combination which comprises a wedge having a part projecting beyond the side of the socket opposite which the wedge is inserted in the socket, and a removable pin mounted in said projecting part of the wedge, said pin projecting outwardly from the wedge for a distance sufficient positively to prevent removal of the wedge from the socket and inwardly from the wedge for a distance sufficient frictionally to engage the interior wall of said socket.

3. In a mining drill head having detachable bits, a wedge for retaining the bits in position and a socket for accommodating the wedge, the improvement which comprises a resilient pin accommodated in a hole in said wedge, one end of said pin being exposed beyond the boundaries of said socket, and the other end engaging an interior wall of said socket at a position concealed by the wedge, said wedge having a recess over-lapping said hole and accommodating the end of said pin which engages the interior socket wall.

4. In a mining drill head having detachable bits, a wedge for retaining the bits in position and a socket for accommodating the wedge, the improvement which comprises a resilient pin accommodated in a hole in said wedge, one end of said pin being exposed beyond the boundaries of said socket, and the other end engaging an interior wall of said socket at a position concealed by the wedge, the hole in the said wedge extending at a substantial angle from the perpendicular to the interior wall of the socket with which the pin engages.

5. A wedge for use with a mining drill having a wedge and bit receiving socket; said wedge being provided with a hole extending diagonally therewith through and terminating at one face in a position which will be exposed when the wedge is disposed within the socket and terminating at the opposite face in a position which will be concealed when the wedge is disposed within the socket, said opposite face of the wedge being provided with a recess overlapping the mouth of said hole and in disalignment therewith.
